FREDERICK J. WEST, MARK JACKSON, AND HAROLD T. LEADER, OF DETROIT, MICHIGAN, ASSIGNORS OF ONE-FOURTH TO ALDRICH BAXTER, OF DETROIT, MICHIGAN.

CONCRETE TUNNEL STRUCTURE.

1,378,158.

Specification of Letters Patent. Patented May 17, 1921.

Application filed December 29, 1920. Serial No. 433,890.

To all whom it may concern:

Be it known that we, FREDERICK J. WEST, MARK JACKSON, and HAROLD T. LEADER, citizens of the United States, residing at 5 Detroit, in the county of Wayne, State of Michigan, have invented certain new and useful Improvements in Concrete Tunnel Structures, of which the following is a description, reference being had to the accompanying drawing and to the figures of 10 reference marked thereon.

The invention relates to new and useful improvements in concrete tunnels or other like tubular structures, and more particularly to a concrete tunnel made up of pre-formed blocks.

An object of the invention is to provide a tunnel structure of the above character wherein the body portion of the tunnel is 20 formed of a series of annular sections interlocked with each other and wherein each section consists of a plurality of curved blocks having tongue and groove connections at their ends and wherein the key block 25 and the blocks associated therewith in said annular sections are so formed that the key block may be put in place by an outward movement from the inner face of the annular section.

30 A further object of the invention is to provide a tunnel construction of the above character wherein the key blocks in adjacent sections are staggered relative to each other.

35 A further object of the invention is to provide a tunnel construction of the above character wherein the key block is held in place by forming opposed grooves in the ends of the key block and in the ends of the 40 sections associated therewith, and inserting in the openings formed by said opposed grooves, keys.

45 A further object of the invention is to provide a structure of the above character wherein the holding keys for the key block are formed from scrap pipe filled with concrete.

50 A still further object of the invention is to provide a tunnel construction consisting of annular sections formed in turn of blocks having interlocking tongues and grooves wherein certain of said blocks are provided with openings during the molding of the blocks, in which openings are placed pipe 55 sections flush with the outer face of the

blocks, and threaded at their inner ends whereby concrete may be caused to flow out through said pipes and fill the space occupied by the shield in the forming of the 60 tunnel.

These and other objects will in part be obvious and will in part be hereinafter more fully disclosed.

In the drawings which show by way of illustration one embodiment of the invention—

Figure 1 is a perspective view showing a portion of a tunnel embodying the improvements;

Fig. 2 is a view in perspective and from the inside of one of the blocks;

Fig. 3 is a side view of one of the blocks;

Fig. 4 is a side view of the key block, parts being broken away to show the pipe construction through which concrete is 75 forced to the outer surface of the tunnel;

Fig. 5 is a similar view of the right-hand block associated with the key block;

Fig. 6 is a similar view of the left-hand block associated with the key block;

Fig. 7 is a detail in side elevation showing one of the key pins, and

Fig. 8 is a sectional view on line a—a of Fig. 3, but showing a modified shaping of the tongue and groove.

The invention is directed broadly to a tubular construction used for tunnels, sewers, culverts, wells, silos, stacks or the like, but preferably for a tunnel construction erected with the aid of a hydraulic shield. The body portion of the tunnel construction consists of series of annular sections which in turn are formed of a series of blocks preferably made of concrete and which are preformed before being placed to 90 form the annular sections. Adjacent blocks are formed at their ends and sides with interlocking tongues and grooves which aid materially in holding the blocks in place during the construction of the annular sections, and also in producing a non-leakable joint when properly mortared between adjacent blocks. These tongues and grooves in the blocks form an interengaging connection between the annular sections and also between the blocks in each section. In each annular section there are two blocks having spaced parallel ends, between which ends is placed a key block. The ends of the key block and the ends of the blocks adjacent 105

thereto, are formed with opposed grooves preferably circular in cross section, and in the circular opening formed by these opposed grooves is placed locking keys preferably made from waste sections of pipe filled with concrete. Certain of the blocks in each annular section as they are formed are provided with pipe sections flush with the inner and outer faces of the blocks, and at the 10 inner face these pipe sections are threaded and adapted to receive a threaded pipe section through which concrete may be forced to the outer wall of the tunnel. As the shield is moved, concrete may be forced 15 through these openings and caused to fill the entire space formed by the shield, and which acts as an outer ring for protecting against settling of the ground, which is very essential, particularly where tunnels 20 or sewers are built under streets and buildings.

Referring more particularly to the drawings, our improved structure consists of a series of annular sections 1. In Fig. 1, we 25 have shown a series of these annular sections placed side by side and thus forming the body portion of the tunnel. Each annular section consists of a series of blocks. These blocks in the main are similar in construction and may be of any suitable size. Said blocks are indicated in the drawings at 30 2. Each block, on one of its side faces has a groove 3, which is preferably semi-circular in cross section. On the opposite face said block is provided with a tongue 3^a which is similar in cross section. At one end said block is provided with a groove 4 which is preferably semi-circular in cross section and the other end of the same block is provided 35 with a tongue or rib 5 which is preferably semi-circular in cross section. It will readily be seen that when the blocks are made up into the annular section, that each section will have on one face a projecting 40 annular tongue and in the other face an annular groove which is adapted to receive a projecting tongue on the next adjacent annular section. These tongues and grooves may, if desired, be rectangular in cross section 45 as shown in Fig. 8.

As above noted, the sections are all similar except the key section and the two blocks on each side thereof associated with the key section. The key section is indicated at 6 55 in Fig. 4 of the drawings. This key section has the usual tongue at the rear side thereof and groove at the forward side thereof. The two ends 7 and 8 are parallel and are both provided with semi-circular grooves 9, 9. 60 These blocks are preferably formed of concrete and when the block is molded it is provided with a pipe 10, which is flush with the outer and inner faces of the block. The inner face of the pipe is enlarged and tapped 65 as indicated at 11, so that the threaded con-

nection may be made with a pipe through which concrete or grout may be forced to the outer face of the tunnel structure. The block at the right of the key section is indicated at 12 in Fig. 5. This block is the 70 same in its shaping and details of construction to the other blocks except that the face 13 is shaped to conform with the face 8 of the key block, that is, said face 13 is parallel with the face 8. The block at the left of the key block is indicated at 14 in Fig. 6 of the drawings. Said block is also similar in construction to the block 12, except that the straight face 15 is at the other end thereof and this face is parallel with the face 7 of the block 6. In other words, the faces 13 and 15 when the blocks are in place in the annular sections are parallel, so that the key block may be inserted by an outward movement from the inner face of the annular section. The end face 15 of the block 14 is provided with a semi-circular groove 18 which is opposed to the groove 9, and together with the groove 9 in the key block form a circular opening. There is a similar groove 19 in the end face 13 of block 12, and this groove 19, together with the groove 9 in the key block form a circular opening. In Fig. 7 there is shown a preferred form 90 of key. Said key consists of a pipe 20 which is filled with concrete and this pipe section 20 is preferably cut from scrap pipe, and of a length to correspond to the width of the block. These keys are inserted in the circular openings between the key block and the adjacent blocks of the annular section, and fill said openings and serve as a locking means to lock the blocks in place. In other words, these keys perform the function of the tongue and groove at the other ends of 100 the blocks, and by forming the end sections with parallel faces, the annular section may be built within the shield, the key block inserted from a point within the opening, and locked in place, after which the shield may 105 be forced forward in the usual way. When the shield is forced forward, blow pipes may be attached to the pipe section 10 in the key block, and to similar pipe sections 10, 10 in the blocks 12 and 14, respectively, and thus 110 concrete forced to the outer wall of the tunnel, completely filling the space occupied by the shield as it is moved forward and thus preventing the settling of the ground in which the tunnel is being built.

While we have shown and described the tongue and groove as semi-circular in cross section, it will be understood that they may be rectangular or in any desired shape. In the building up of the annular sections, the key block 6 of one section is preferably staggered relative to the key block of the next adjacent section, said key blocks being indicated at 6 and 6' in Fig. 1. Likewise the key block of the next section which is 115 120 125 130

5 indicated at 6² is staggered relative to the key block 6'. It will also be noted that all the block sections are staggered relative to each other or arranged so as to break joints. A portion of the shield is indicated at S in Fig. 1.

10 The continuous tongue and groove joint between annular sections forms a very durable side lock and prevents seepage, and allows the blocks to be made of any size desired. These tongues and grooves between the sections also prevent radial displacement of one section relative to the other and hold the sections in alinement. The 15 tongues and grooves at the ends of the blocks serve to lock the blocks firmly in place and prevent any radial displacement thereof by the earth crushing in on the annular sections as often occurs. These interlocking tongues and grooves also form a locking between the blocks while erecting the annular sections. In laying a horizontal tunnel, the blocks are started at the bottom and built up on both sides, and when the 20 top is reached, a key block may be pushed straight up into place and locked in place by the keys filled with concrete.

25 It is obvious that minor changes in the details of construction may be made without departing from the spirit of the invention as set forth in the appended claims.

Having thus described the invention, what we claim as new and desire to secure by Letters Patent, is:—

35 1. A tunnel or like structure comprising annular sections, each annular section consisting of a series of curved blocks, means integral with said blocks for holding said blocks against radial displacement in the 40 annular sections and said annular sections in alinement, two of said blocks having spaced parallel ends adapted to receive therebetween a key block, and means integral with said key block for securing said 45 key block against radial displacement when inserted in place.

50 2. A tunnel or like tubular structure comprising annular sections consisting of curved blocks having interengaging tongues and grooves at the ends thereof, two of said blocks having their adjacent ends spaced and parallel with each other and adapted to receive therebetween a key block, and means for holding the key block in place, 55 said blocks and key blocks of each annular section having interfitting lateral tongues and grooves to hold said blocks from radial displacement and said sections in alinement.

60 3. A tunnel or like tubular structure com-

prising annular sections consisting of curved blocks having interengaging tongues and grooves at the ends thereof, two of said blocks having their adjacent ends spaced and parallel with each other and adapted to receive therebetween a key block, said key block at its ends and the ends of the adjacent blocks having opposed grooves, and keys adapted to be placed in said opposed grooves for securing the key block in place. 65

4. A tunnel or like tubular structure comprising annular sections consisting of curved blocks having interengaging tongues and grooves at the ends thereof, two of said blocks having their adjacent ends spaced and parallel with each other and adapted to receive therebetween a key block, said key block at its ends and the ends of the adjacent blocks having opposed grooves, and keys adapted to be placed in said opposed 70 grooves for securing the key block in place, 75 said keys consisting of scrap pipe cut to suitable length and filled with concrete.

5. A tunnel or like tubular structure comprising annular sections consisting of curved blocks having interengaging tongues and grooves at the ends thereof, two of said blocks having their adjacent ends spaced and parallel with each other and adapted to receive therebetween a key block, and means for holding the key block having parallel ends in place, certain of said blocks in each annular section having pipes extending from front to rear and flush with the inner and outer faces thereof, through which grout may be forced to the outer surface of the tunnel for filling the space occupied by the shield when moved forward. 85

6. A tunnel or like structure comprising annular sections, means for holding said annular sections in alinement, each annular section consisting of a series of curved blocks, means for holding said blocks against radial displacement in the annular sections, two of said blocks having spaced parallel 100 ends adapted to receive therebetween a key block having parallel ends, and means for securing said key block against radial displacement when inserted in place, certain of said blocks having pipes extending from front to rear thereof and flush with the outer surfaces through which grout may be forced to the outer surface of the annular sections. 105

110 In testimony whereof, we affix our signatures.
